UNITED STATES PATENT OFFICE

2,426,906

MANUAL RESET THERMOSTATIC SWITCH
IN PROTECTIVE SYSTEMSVictor G. Vaughan, Attleboro, Mass., assignor to
Metals & Controls Corporation, Attleboro,
Mass., a corporation of Massachusetts

Application June 28, 1943, Serial No. 492,555

11 Claims. (Cl. 175—294)

1

This invention relates to electrical protective apparatus, and with regard to certain more specific features, to thermostatically controlled protective means for electric motors and the like.

Among the several objects of the invention may be noted the provision of mechanically and electrically simple protection apparatus for electrical energy translating devices (for example a motor or transformer) which allows manual reset means to be located at a distance from the protected apparatus while only small and compact parts are mounted on the casing of the protected apparatus. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which are illustrated several of various possible embodiments of the invention,

Fig. 1 is a wiring diagram showing one form of the invention; and,

Fig. 2 is a wiring diagram showing a second form.

Similar reference characters indicate corresponding parts throughout the several views of the drawing.

Referring now more particularly to Fig. 1, there is shown at M a motor which is to be protected against overheating due either to overload or high ambient temperature. The circuit supplying the motor is shown at C. At numeral 1 is shown an automatic reset thermostatic protective assembly which it is intended shall be small enough to be mounted upon the motor casing, or at least be in the close vicinity of the motor so as to be responsive to ambient temperature conditions around the motor.

At 3 is shown a manual reset thermostatic assembly intended to be remotely located with respect to the motor.

Assembly 1 has main contacts 5 and 7. Contact 5 is connected with the circuit C by wire 9. Contact 7 is connected with a third contact 11 by way of a resistance heater 13 which is located closely adjacent to an automatic reset thermostatic element 15. The mechanical details of the thermostatic element 15 are shown in United States Patent 2,199,387. Thus 15 is a bimetallic snap-acting thermostatic disc which upon temperature rise from normal temperature conditions snaps to an opposite curvature, thereby removing

2

contacts 17 and 19 carried thereby from the contacts 5 and 7. Upon reduction in temperature, the disc 15 snaps back to the curvature shown to reclose contacts 5, 19 and 7, 17. It is classified as an automatic reset thermostat.

The assembly 3 is composed of stationary contacts 21 and 23 in a line 25, and terminals 27 and 29 between which is a resistance heater 31. The contacts 27 and 29 are in a circuit 33 which connects across the contacts 5 and 7 in assembly 1.

A thermostatic disc 35 of the snap-acting type carries movable contacts 37 and 39 for opening and closing the contacts 21 and 23 in line 25. The thermostatic disc 35 is of the so-called manual reset type, which recloses only by manual operation of a reset button 41. That is to say, if the disc 35 snaps to open position upon heating, it will remain in that position until reset manually, even though the temperature again is reduced to normal. The details of a typical manual reset thermostat are disclosed in United States Patent 2,199,388.

Operation is as follows:

When the motor M is energized over the line 25 C, current flows through the motor, line 8, contacts 5, 19, thermostatic disc 15, contacts 17, 7, resistance 13, line 25, contacts 23, 39, disc 35, contacts 37, 21 and back to the line C. No substantial current at this time flows through the resistance 31, since there is very little potential applied across this resistance, the resistance of disc 15 being low.

If the motor becomes electrically overloaded, or overheated, the thermostatic disc 15 will respond by snapping to reverse curvature and remove contacts 17, 19 from contacts 5, 7. Heater 13 accelerates the heating of the disc 15. With 15 open, current will thus be forced to flow from the line C through terminal 21, heater 31, terminal 29, line 33, contact 7, heater 13, terminal 11, line 25, returning to the line C through the contacts 23, 39, disc 35, contacts 37 and 21, back to the line C. Heating of the disc 35 by the adjacent heater 31 causes the disc 35 to open the line 25 which at this time forms the only connection closing the circuit C. Once the disc 35 snaps to open position, it will remain there until reset by manual operation on the button 41. Thus even though disc 15 may reclose, a manual reclosure at 41 is necessary.

From the above it will be seen that the effect of operation of the automatic reset disc 15 is to open and shut the circuit across the resistance 31, thus acting as a relay. After the disc 35 has once operated to break the circuit, it does not matter

that the automatic disc 15 recloses the contacts 5, 19 and 7, 17 because then the circuit C is in any event broken at contacts 21 and 23.

Advantages of the invention are that the relay assembly 1 may be made small and sensitive and mounted on or near the motor while the assembly 3 may be made larger in its remote location.

At Fig. 2 is shown a form of the invention arranged so that the resistance 13 in the assembly 1, when 15 is open, is not (as in Fig. 1) in series with the resistance 31. To this end, the connection 33 and contact 29 are eliminated and the resistance 31 is connected between terminal 27 and contact 28 of the reset switch 3. In this case, overload current first passes through connection 9, disc 15, heating resistance 13, line 25, disc 35 and back to the line C. The heater 13 causes disc 15 to snap open initially, whereupon the circuit traces from line C to terminal 27 in assembly 3, heater resistance 31, disc 35 and back to the line C. The heater 31 then causes opening of the thermostatic element 35 which completely breaks the motor circuit. This allows the automatic reset thermostat 1 to return to position prior to resetting the reset thermostat 3, without placing the motor back in the line.

It will be understood that the invention will provide protection for other translating or similar apparatus equivalent to the motor shown.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. Electrical protective means in a supply circuit, comprising a manual reset thermostat, an automatic reset thermostat, a heater element associated with each of said thermostats, a circuit placing the manual reset thermostat in series with the heater element of the automatic reset thermostat, means connecting the automatic reset thermostat so that when cold it shunts the heater element of the manual reset thermostat and when hot opens said shunt, and circuit means which places said heater element of the manual reset thermostat in series connection with said manual reset thermostat when said shunt is open.

2. Electrical protective means in a supply circuit comprising a manual reset thermostat, an automatic reset thermostat, a heater element associated with each of said thermostats, a circuit placing the manual reset thermostat in series with the heater element of the automatic reset thermostat, means connecting the automatic reset thermostat, so that when cold it shunts the heater element of the manual reset thermostat and when hot opens said shunt, circuit means which places said heater element of the manual reset thermostat in series connection with said manual reset thermostat when said shunt is open, said last-named circuit means being arranged to connect both of said heater elements in series when said shunt is open.

3. Electrical protective means in a supply circuit comprising a manual reset thermostat, an automatic reset thermostat, a heater element associated with each of said thermostats, a circuit placing the manual reset thermostat in series with the heater element of the automatic reset thermostat, means connecting the automatic reset

thermostat so that when cold it shunts the heater element of the manual reset thermostat and when hot opens said shunt, circuit means which places said heater element of the manual reset thermostat in series connection with said manual reset thermostat when said shunt is opened, said last-named circuit means being arranged to cut out of circuit the heater element of the automatic reset thermostat when said shunt is open.

4. In apparatus of the class described, an automatic reset thermostat assembly and a manual reset thermostat assembly, a thermostatic switch member and a heater in the automatic assembly and a thermostatic switch and a heater in the manual assembly, the thermostatic switch of the automatic assembly, its heater and the thermostatic switch of the manual assembly being normally in series, the thermostatic switch of the automatic assembly when closed shunting the heater of the manual assembly.

5. In apparatus of the class described, an automatic reset thermostat assembly and a manual reset thermostat assembly, a thermostatic switch member and a heater in the automatic assembly and a thermostatic switch and a heater in the manual assembly, the thermostatic switch of the automatic assembly, its heater and the thermostatic switch of the manual assembly being normally in series, the thermostatic switch of the automatic assembly when closed and its heater shunting the heater of the manual assembly.

6. In apparatus of the class described, an automatic reset thermostat assembly and a manual reset thermostat assembly, a thermostatic switch member and a heater in the automatic assembly and a thermostatic switch and a heater in the manual assembly, the thermostatic switch of the automatic assembly, its heater and the thermostatic switch of the manual assembly being normally in series, the thermostatic switch of the automatic assembly when closed shunting the heater of the manual assembly and said heaters being in series connection when the automatic reset thermostat is open.

7. In apparatus of the class described, an automatic reset thermostat assembly and a manual reset thermostat assembly, a thermostatic switch member and a heater in the automatic assembly and a thermostatic switch and a heater in the manual assembly, the thermostatic switch of the automatic assembly, its heater and the thermostatic switch of the manual assembly being normally in series, the thermostatic switch of the automatic assembly when closed and its heater shunting the heater of the manual assembly and when the automatic reset thermostat is open said heater in the manual assembly being in series connection with the manual reset thermostat and the heater in the automatic assembly being disconnected.

8. In apparatus of the class described, an automatic reset thermostatic switch and a heater therefor, a manual reset thermostatic switch and a heater therefor, the automatic thermostatic switch, its heater and the manual thermostatic switch being normally in series, the automatic thermostatic switch when automatically closed shunting the heater of the manual thermostatic switch, and means forming a series connection between the two heaters when the automatic thermostatic switch is open.

9. In apparatus of the class described, an automatic reset thermostatic switch and a heater therefor, a manual reset thermostatic switch and a heater therefor, the automatic thermostatic

switch, its heater and the manual thermostatic switch being normally in series, the automatic thermostatic switch when automatically closed shunting the heater of the manual thermostatic switch, and means for cutting out of circuit the heater for the automatic reset switch when the latter is open.

10. Electrical protective means in a supply circuit comprising a manual reset thermostat, an automatic reset thermostat, a heater element 10 associated with each of said thermostats, a circuit placing the manual reset thermostat in series with the heater element of the automatic reset thermostat and with the automatic reset thermostat, means connecting the automatic reset thermostat so that when cold it shunts the heater element of the manual reset thermostat and when hot opens said shunt, and circuit means which places said heater element of the manual reset thermostat in series connection with said manual reset thermostat when said shunt is open.

11. Electrical protective means in a supply circuit comprising a manual reset thermostat, an automatic reset thermostat, a heater element associated with each of said thermostats, a circuit 20 placing the manual reset thermostat in series

with the heater element of the automatic reset thermostat and with the automatic reset thermostat, means connecting the automatic reset thermostat so that when cold it and its heater shunt the heater element of the manual reset thermostat and when hot it opens said shunt, and circuit means which places said heater element of the manual reset thermostat in series connection with said manual reset thermostat when said shunt is open.
